Primary Examiner—Cathron B. Matta*Attorney, Agent, or Firm*—Foley & Lardner[57] **CLAIM**

The ornamental design for a screen, as shown and described.

DESCRIPTION

FIG. 1 is a rear perspective view of the screen according to a preferred embodiment.

FIG. 2 is a front perspective view of the screen.

FIG. 3 is a front elevation of the screen.

FIG. 4 is a top plan view of the screen.

FIG. 5 is a side elevation of the screen; and,

FIG. 6 is a rear elevation of the screen.

The broken lines at the perimeter of the screen portion of the claimed design define the bounds of the claimed design and form no part thereof.

The conventional drafting break lines indicate indeterminate height and width of the claimed design.

The broken line showing of a horizontal divider is for illustrative purposes only and forms no part of the claimed design.
